CLAIM

The ornamental design for a paintball, as shown.

DESCRIPTION

The file of this patent contains at least one drawing/photograph executed in color. Copies of this patent with color drawing(s)/photograph(s) will be provided by the Office upon request and payment of the necessary fee.

FIG. 1 is a side view of a paintball showing my new design; FIG. 2 is a view rotated approximately 180° clockwise from FIG. 1, and then toward the right around a nearly vertical axis to expose a portion of the left-hand side of FIG. 1; FIG. 3 is a view rotated approximately 180° clockwise from FIG. 1, and then towards the left around a nearly vertical axis to expose the rear together with a portion of the right-hand side of FIG. 1; and,

FIG. 4 is a view rotated approximately 90° clockwise from FIG. 3 and again towards the lower left to expose a portion of the upper right hand side of FIG. 3.
